UNITED STATES PATENT OFFICE

WALTER O. SNELLING, OF ALLENTEWON, PENNSYLVANIA

PLAYING CARDS

Application filed December 8, 1928. Serial No. 324,685.

My invention relates to improvements in playing cards, and more particularly relates to an improved educational card game. One of the objects of my invention is to provide a card game in which such elements as perception, mental quickness and reasoning ability will form important factors of success, and will equal or overshadow the element of chance resulting from the nature 10 of the cards received from the dealer.

For purpose of clarity I will refer to the two principal types of cards which I may employ in conjunction with my present invention as "window" cards and "base" 15 cards. By "window" card is meant a card having one or more holes, openings or windows therein, in conjunction with words or symbols upon the face of the card in association with such windows, the purpose 20 of the windows being to make visible other symbols upon an underlying card necessary to complete an incomplete series of symbols upon the face of the window card. It is not necessary that all of the combinations of 25 symbols upon a window card should be incomplete, since complete series of symbols may be used upon a window card in conjunction with incomplete series associated with windows, to any extent desired. By base 30 card is meant a card which is not provided with windows, but which is provided with intelligible symbol aggregates which may or may not represent true or correct statements or equations or aggregates of symbols, but 35 which may be differentiated upon the basis of their correctness or incorrectness.

Although I prefer to employ an opening cut through a card as a window, I do not wish to be limited to openings as windows, 40 as I may apply any suitable oily or waxy material to a limited portion of a card, for the purpose of forming a window therein, in the same manner that the windows upon mailing envelopes are now produced. Similarly, I may employ a sheet of transparent or translucent cellulose such as viscose, or a sheet of transparent or translucent 45 pyroxylin plastic such as nitrocellulose, to form closed but transparent windows in the 50 window cards herein described.

In the accompanying drawings Fig. 1 to Fig. 4 represent plan views showing the face of playing cards illustrating certain forms that my invention may take.

In the drawings Figure 1 is one card 55 from a pack or deck, illustrating the present invention, and Figure 2 is a second card from the same pack or deck, but differing in type from the card shown in Figure 1. For the purpose of simplifying the present description all symbols have been omitted from the illustrations which are not of significance in explaining their operation.

In Figure 1, *c* is a window card, upon 60 which certain symbols have been inscribed as shown. In addition to these symbols, this card contains certain holes, openings or windows, *h*, *h*¹, etc. In Figure 2, *c* is a reversible base card, upon which certain 65 symbols have been inscribed as shown, part of these symbols being in correct position when the edge of the card marked *A* is uppermost, and part of these symbols being in correct position when the edge of the 70 card marked *B* is uppermost.

In Figure 3, *c* is a window card upon 75 which certain symbols have been inscribed as shown and which also contain certain windows *h*, *h*¹, etc. Figure 4 is a similar window card, also provided with certain 80 symbols and windows, the card shown in Figure 4 being capable as serving as a base card when a card as shown in Figure 3 is placed upon it, while similarly the card shown in Figure 4 may serve as a window 85 card if superimposed over the card shown in Figure 3.

It will be noted that the card shown in Figure 1 is primarily a window card, the card shown in Figure 2 is primarily a base 90 card, and the cards shown in Figures 3 and 4 may be used interchangeably as window cards or as base cards. Accordingly the distinction between window cards and base cards 95 is not entirely definite, although it is often convenient to so distinguish the different types of cards used.

The second line of symbols upon the card shown in Figure 2 is shown complete, with 100 symbols both upright and reversed in each

of the positions in which such symbols appear upon an actual card. In the other lines symbols not involved in the present illustration have been omitted for the purpose of avoiding undue complexity. As indicated in Figure 2, the symbols upon a base card may be isolated and meaningless in themselves, or unassociated with a window card, or may form complete sets of symbols, words or equations entirely intelligible when standing alone but equally capable of forming a part of a second set of symbols when overlaid by a window card.

In order to illustrate one way in which my present invention may be applied, I will assume a pack or deck of twelve cards of the general type shown in Figure 1, and sixty cards of the general type shown in Figure 2, all of the cards of both types 1 and 2 being different with respect to the symbols placed thereon. Any desired number of cards of type 1, and any desired number of cards of type 2, may be dealt out to each player, but for purpose of simplification I will assume that but one card of type 1 and four cards of type 2 are dealt out to each player. Upon placing card 1 over card 2, so that the two cards are superimposed with their edges in contact, it will be noted that the composite card formed by these two cards thus positioned contains a number of statements, part of which are complete upon card 1, and part of which are only completed by the symbols which are present on card 2, and which become apparent through the windows h , h^1 , etc. on card 1. Part of the statements are true, and part of the statements are untrue. If card 1 is placed over card 2 with the A edge of card 2 uppermost, then the following statements will be shown:

$$\begin{aligned}
 4 \times 4 &= 16 \\
 2 : 3 :: 8 : 16 \\
 3 \times 4 &= 8 + 4 \\
 18 \div 2 &= 9 - 3 \\
 45 \quad 20 \text{ objects make a doz.} \\
 25 - 11 &= 7 \times 3 \\
 3 + 4 + 5 &= 13
 \end{aligned}$$

Obviously, statements 1 and 3 are correct, 50 and 2, 4, 5 and 6 and 7 are incorrect.

If, however, card 1 is placed over card 2 so that the B edge of card 2 is uppermost then the following statements will be shown:

$$\begin{aligned}
 55 \quad 4 \times 4 &= 18 \\
 2 : 3 :: 8 : 12 \\
 3 \times 4 &= 8 + 4 \\
 18 \div 3 &= 9 - 3 \\
 60 \quad 12 \text{ objects make a doz.} \\
 25 - 11 &= 7 \times 2 \\
 3 + 4 + 5 &= 13
 \end{aligned}$$

It will be obvious that in the present case statements 2, 3, 4, 5 and 6 are correct, and 1 and 7 are incorrect.

65 If we give the composite card a playing

value equal to the number of correct statements that occur upon it, it will be evident that cards 1 and 2, with card 2 with its A side uppermost, will have a playing value of 2, but with its B side uppermost, will have a playing value of 5. If, as we have assumed, the player has one card corresponding to card 1, and four cards corresponding to card 2, it will be evident that by trying in turn each of the four cards of the type shown by Fig. 2, and by reversing each of these cards so as to find which one of the eight possibilities gives the highest value, a skillful player can obtain a high value for his composite card, by a proper selection of the card of type 4 that he employs with the card of type 1.

In ordinary play, two or more cards of type 1, and six or more cards of type 2, would be dealt to each player, who would then arrange the cards so as to obtain the highest possible combination by the wise selection of the cards to be used in association.

The cards shown in Figure 3 and Figure 4 represent two cards from a pack or deck of variable value window cards, adapted to be used without special base cards, a window card being laid over another window card to form a composite card pair unit which is played as a single card. If card 3 is laid over card 4, the following statements would be shown:

$$\begin{aligned}
 15 + 5 &= 9 + 11 \\
 11 - 3 &= 5 + 3 \\
 20 \div 3 &= 12 - 3 \\
 12 : 9 :: 18 : 15 \\
 6 \times 8 &= 50 - 2 \\
 7 + 10 &= 30 \div 2 \\
 3 + 4 + 5 &= 12
 \end{aligned}
 \quad \begin{array}{r} 100 \\ 105 \end{array}$$

It will be evident that lines 1, 2, 5 and 7 represent correct or true statements and that lines 3, 4 and 6 represent incorrect or untrue statements. Accordingly, when card 3 is placed over card 4, the card pair unit has a playing value of 4. If card 4 overlies card 3 however, the following statements would be shown:

$$\begin{aligned}
 24 \div 5 &= 9 - 3 \\
 11 \times 3 + 2 &= 24 \\
 20 - 6 &= 2 \times 3 \\
 13 + 8 &= 18 + 15 \\
 8 \times 8 &= 50 - 12 \\
 7 + 10 &< 7 + 7 \\
 3 \times 9 &= 30 - 12
 \end{aligned}
 \quad \begin{array}{r} 115 \\ 120 \end{array}$$

Upon inspection, it will be observed that not one single statement in the above list is correct. Accordingly, the good player will place card 3 upon card 4, to obtain a playing value of 4, while the same two cards would have a playing value of 0, if card 4 were placed upon card 3. In a pack of cards running from 24 cards to 72 cards for example, a remarkably wide range of selec-

tion is possible, and a good player will obtain a number of card pairs having playing values of 5, 6 or 7, where a less skillful player will only be able to obtain average values of 3 or under.

5 The maximum playing value that any single card or any unitary pair of cards can have is of course limited by the number of lines or equations or symbol aggregates that 10 are used upon such cards. In the illustration each card is shown to have seven lines, and accordingly would have a playing value of 7 if all of the statements or equations were correct. In practice I have found 15 7 lines to a card to be a convenient number, but for advanced players cards containing 10 or 12 lines or symbol aggregates may be used, and similarly for inexperienced or juvenile players cards containing only 2 or 20 3 lines may be employed, in order to avoid unduly fatiguing the player by the necessity of making an excessive number of mental calculations for each of the many combinations that his cards may make possible.

25 Many entirely different card games involving elements of both chance and skill may be played with cards of the kind herein described, in just the same way that many dozens of entirely different card games may 30 be played with a deck of ordinary playing cards. I do not wish to limit myself to any particular game that may be played with cards as herein described, but for purpose of illustration I will describe one game, having 35 some similarity to the game of whist as played with an ordinary deck of playing cards. After thorough shuffling three window cards and six base cards would be dealt in rotation to each of the four players. A 40 time limit of say three minutes, which may be conveniently measured by a small sand timing glass is allowed between the time of completing the dealing of the cards and the laying down of the first card by the player 45 to the left of the dealer. Within this period of three minutes the different players would arrange their cards so as to get the highest values possible, and each player would then in turn place upon the table in front of him 50 the highest card that he could make by the combination of any window card in his hand with any base card in his hand, the player playing the highest card taking the trick, and leading in the next play.

55 It will be obvious that the game as thus described will be most suitable for a mentally alert person, and it is also true that for good playing the game will tax the ability of a person of excellent reasoning faculties. 60 Each combination that is tried of a window card with a base card, (and in either of the positions in which the base card can lie in the case of reversible base cards) will involve the solving of a number of mathematical 65 problems, and the players will score in ac-

cordance with their ability to make the most of their cards to such an extent that the ability factor can if desired be made to quite overshadow the element of chance involved in the deal itself.

70 For younger or less experienced players, cards involving the general principles of the cards herein described, but containing relatively simple mathematical problems or wholly non-mathematical statements may be substituted. Instead of such a statement as "4×4=○", (the symbol ○ being used herein to indicate a window) as shown on the first line of card 1, there can be used, for example a sentence such as "A rose is 80 ○", and in this case on the underlying card circles of various colors such as red, blue, green and violet could be used, in place of the numbers shown on the present cards. By proper selection of a window card and 85 a base card, the skillful juvenile player could so arrange a pair of cards that a red circle underlies the window at the end of the sentence "A rose is ○", and a card so arranged would score over a card in which the color 90 disk on the base card was green, blue or violet. Thus a pack or deck of cards involving the present invention could be made that would be entirely suitable for very young 95 players, and the game thus constituted has 100 very great educational value, in quickening the perceptive and reasoning faculties. For mature players cards involving advanced mathematics could be used, or for non-mathematical advanced players other appropriate 105 groups of statements could be used. Thus, in a set of cards for chemists, such statements as "The atomic weight of aluminum is ○", and "Sulfur units with oxygen to form ○" could be used, the first statement 110 being correct when a base card having 27 under the first window was selected, and the second statement being correct when a base card having SO₂ under the second window was selected. The application of the present invention to problems involving algebra, trigonometry, square root, cube root, differential and integral calculus, permutations and combinations and other advanced mathematics will of course be obvious.

115 Instead of employing window cards and base cards in conjunction, I may employ cards without windows exclusively, or I may have windows in all of my cards, in this case the windows exposing symbols upon an underlying card that when not thus covered by another card may or may not form part of an entirely independent statement, sentence or set of symbols.

120 An exceptionally wide variety of types of playing cards may be made in accordance with my present invention. I may employ base cards of one color, shade or tint and window cards of another color, shade or tint, or I may make both base cards and 125

130

window cards of paper or other suitable material without differentiation except as to the symbols imprinted upon such cards. The holes or windows may differ in shape, size or location, or may be further differentiated by being bordered by a small band of color, which may if desired be different on different cards. The symbols used may differ in style of type, color of ink, or in any other desired characteristic. The cards may be symmetrical with respect to either the vertical axis of the card or symmetrical with the horizontal axis of the card or symmetrical as to neither. I prefer to employ base cards that are reversible, as shown in Figure 2, and with symbols that are so arranged as to always show through the windows in proper position regardless of which end of the base card is uppermost, but this is not essential.

I may entirely dispense with base cards, all of my cards being window cards as shown in Figure 3 and Figure 4, or I may entirely dispense with window cards and only employ cards without windows or openings. The cards may be made with relatively few complete and with many or all incomplete sets of symbols, or may be made with relatively few incomplete sets of symbols and with many or all sets of symbols entirely complete. Any individual card may contain few or many correct symbol sequences and few or many incorrect symbol sequences, as may be desired. Although I prefer to use digits or numbers mainly in forming my symbol sequences, I may employ colors, letters, words, or other desired types of symbols. If desired the base cards may be complete in themselves or may be used in conjunction with the window cards to any desired extent. For example, if a base card had a playing value of 5 before being covered by a window card and a playing value of but 4 when covered by the best window card in the hand of the player, it would be more desirable to play it uncovered, or to place the base card over the window card and then play the composite card thus formed, unless the rules of the particular game that was being played forbid this form of play.

In view of the great number and wide variety of changes that may be made in the design of playing cards made in accordance with my present invention I do not wish to be limited to any of the specific illustrations herein given, since all of these have been shown for purpose of illustration and not by way of limitation, and accordingly no limitations should be placed upon my invention except such as are indicated in the appended claims.

I claim:

65 1. Playing cards comprising a plurality

of cards each inscribed with a plurality of groups of symbols forming individual intelligible combinations, some combinations of symbols being correct and some combinations of symbols being incorrect, the playing value of any card being determined by the number of correct combinations upon it. 70

2. Playing cards comprising a plurality of cards each card inscribed with a plurality of statements, some statements being correct and some statements being incorrect, the playing value of any card being determined by the number of correct combinations upon it. 75

3. Playing cards comprising a plurality of cards inscribed with a plurality of incomplete groups of symbols in association with windows through which additional symbols necessary to complete such groups may be shown, some combinations of symbols being correct and some combinations being incorrect. 80 85

4. Playing cards comprising a plurality of cards inscribed with a plurality of incomplete groups of symbols in association with windows through which additional symbols necessary to complete such groups may be shown, some combinations of symbols being correct and some combinations being incorrect, the playing value of any card being determined by the number of correct combinations upon it. 90 95

5. Playing cards comprising a plurality of cards each inscribed with one or more groups of symbols forming intelligible combinations and one or more incomplete groups of symbols in association with windows through which additional symbols necessary to complete such incomplete groups may be shown, some combinations of symbols being correct and some combinations being incorrect. 100 105

6. Playing cards comprising a plurality of cards each inscribed with one or more groups of symbols forming intelligible combinations and one or more incomplete groups of symbols in association with windows through which additional symbols necessary to complete such incomplete groups may be shown, some combinations of symbols being correct and some combinations being incorrect, the playing value of any card being determined by the number of correct combinations upon it. 110 115

7. Playing cards comprising a plurality of window cards and a plurality of base cards each window card being inscribed with a plurality of groups of incomplete symbols each in association with a window and each base card being inscribed with a plurality of symbols capable of being seen through such windows of a window card properly placed upon it and capable of completing the set of symbols to form an intelligible combination, some combinations of symbols 120 125 130

being correct and some combinations of symbols being incorrect.

8. Playing cards comprising a plurality of window cards and a plurality of base cards each window card being inscribed with a plurality of groups of incomplete symbols each in association with a window and each base card being inscribed with a plurality of symbols capable of being seen through such windows of a window card properly placed upon it and capable of completing the set of symbols to form an intelligible combination, some combinations of symbols being correct and some combinations of symbols being incorrect, the playing value of any group of a base card and a window card lying upon it being determined by the number of correct combinations upon the composite card unit.

20 In testimony whereof, I have hereunto subscribed my name this 5th day of December, 1928.

WALTER O. SNELLING.
